DESIGN FOR A DRAWER PULL

Carl W. Carlson, Rockford, Ill.

Application February 26, 1938, Serial No. 75,422

Term of patent 3½ years

To all whom it may concern:

Be it known that I, Carl W. Carlson, a citizen of the United States, residing at Rockford, in the county of Winnebago and State of Illinois, have invented a new, original, and ornamental Design for a Drawer Pull, of which the following is a specification, reference being had to the accompanying drawing, forming part thereof.

In the drawing, Figure 1 is a front elevational view of a drawer pull showing my new design.

Fig. 2 is a top plan view.

Fig. 3 is a bottom plan view.

Fig. 4 is an end elevation.

Fig. 5 is a section taken along the line 5—5 of Fig. 1.

The design is especially characterized by the fact that the base and the handle proper are made of different materials or of contrasting colors.

I claim:

The ornamental design for a drawer pull, substantially as shown and described.

CARL W. CARLSON.
